(57) **CLAIM**

The ornamental design for a mobile payment tablet, as shown and described.

DESCRIPTION

FIG. 1 is a top, front, right side perspective view of a mobile payment tablet, showing my new design;

FIG. 2 is a bottom, rear, right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a bottom, rear, right side perspective view of the mobile payment tablet thereof, showing a graphic.

The broken lines in the drawings illustrate portions of the mobile payment tablet and form no part of the claimed design. The other broken lines in FIG. 9, showing a graphic, represent environmental subject matter only and form no part of the claimed design.

1 Claim, 9 Drawing Sheets
